US0D1067459S

(12) United States Design Patent (10) Patent No.: US D1,067,459 S
(45) Date of Patent: * Mar. 18, 2025

(54) CAPSULE

(71) Applicant: Droplette Inc., Boston, MA (US)

(72) Inventors: Madhavi Gavini, Cambridge, MA (US); Rathi Srinivas, Boston, MA (US); Peter Stokes, Boston, MA (US); Danny Lee, Somerville, MA (US); Rebecca Conway, Boston, MA (US)

(73) Assignee: DROPLETTE INC., Boston, MA (US)

() Term: 15 Years

(21) Appl. No.: 29/810,066

(22) Filed: Sep. 30, 2021

(51) LOC (15) Cl. 24-02

(52) U.S. Cl.

USPC D24/224; D24/188; D9/696

(57) CLAIM

The ornamental design for a capsule, as shown and described.

DESCRIPTION

FIG. 1 is a perspective view of a capsule, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the drawings depict portions of the capsule and form no part of the claimed design.

1 Claim, 4 Drawing Sheets
